(57) **CLAIM**

The ornamental design for a rotating bracket for linear lighting, as shown and described.

DESCRIPTION

FIG. 1 is a perspective view of a rotating bracket for linear lighting, illustrating our new design;

FIG. 2 is a front elevational view;

FIG. 3 is a rear elevational view;

FIG. 4 is a top plan view;

FIG. 5 is a bottom plan view;

FIG. 6 is a left elevational view; and,

FIG. 7 is a right elevational view.

In the drawing figures, areas of the rotating bracket enclosed by broken lines form no part of the claim, and structure illustrated in broken lines also forms no part of the claim.
